UNITED STATES PATENT OFFICE.

LOUIS SARKIS HARPOOTIAN, OF BROOKLYN, NEW YORK.

SELF-FEEDING, PORTABLE, TYPEWRITER-RIBBON INKER.

1,411,212.

Specification of Letters Patent. Patented Mar. 28, 1922.

Application filed January 13, 1921. Serial No. 437,066.

To all whom it may concern:

Be it known that I, LOUIS S. HARPOOTIAN, a native of Armenia, Turkey, who in the Supreme Court of the State of New York, 5 Kings County, on March 30th, 1920, made declaration of my intention to become a citizen of the United States of America, and resident of No. 9435 Ridge Boulevard, borough of Brooklyn, in the city of New 10 York, in the county of Kings and State of New York, have invented a certain new and useful Self-Feeding, Portable, Typewriter-Ribbon Inker, of which the following is a specification.

15 The objects of my invention are, first, to provide an implement for re-inking typewriter ribbons on the typewriter or wherever the ribbons may be; second, to provide an implement which can be carried and 20 held in the hand and not attached to the typewriter; and third, to accomplish said object by an implement containing an automatic ink feeder.

I attain these objects by the mechanism 25 illustrated by the accompanying drawing, in which Figure 1 is a side elevation of the entire implement; Figure 2, a plan view from above of the tube or ink container showing the slot with the clamp removed; 30 Figure 3, a side elevation of the clamp; Figure 4, a side elevation of the spring; Figure 5, a longitudinal view from below of the ring to which the clamp is joined; Figure 6, a side elevation of the cap; and 35 Figure 7, the liquid absorbent material.

Similar numerals refer to similar parts throughout the several views.

1 is a metal tube or receptacle to contain the ink, plugged at one end and fitted with 40 the removable cap 2 at the other end.

In the upper side of the tube 1 is the slot 3 and into this slot is fitted the liquid absorbent material 4 with an outer edge exposed which comes in contact with the ribbon to be inked.

5 is a metal clamp joined to the tube 1 at 6 in the manner described below, so that the end 7 will be raised or lowered as pressure is applied or removed from the end 8.

50 9 is a metal spring to hold the end 7 at the proper pressure against the ribbon when it is passed over the liquid absorbent material 4 in the slot 3. The spring is clasped

to the tube 1 by the ring 10 and may be slid backward or forward along the tube as a 55 means of regulating the tension of the spring.

The metal clamp 5 is joined to the tube 1 as follows: In each side of the metal ring 11 there is a projection or tenon 12, 12, which 60 fits into a corresponding indentation or mortise 6 in the clamp 5.

The way to use this ribbon inker when the ribbon is on a typewriter is as follows: Fill the tube or barrel of the inker with the ink 65 just as you would a fountain pen. Invert the inker to thoroughly saturate the pad with the ink. Wind the ribbon on the left spool of the typewriter. Place the ribbon between the clamp and tube near the right 70 spool, and turn the spool so that the entire length of the ribbon is drawn through the inker. Then the ribbon is practically new.

I claim:

1. The combination in a ribbon inking 75 machine of a tube or barrel to contain ink, having one end closed and the other end fitted with a removable cap, said tube having a slot to receive a liquid absorbent material; said liquid absorbent material; and a clamp 80 joined to the tube or barrel by means of a ring clasped around said tube having on either side a projection or tenon fitting into a corresponding indentation or mortise in the clamp, all substantially as described and 85 illustrated in the accompanying drawing.

2. The combination in a ribbon inking machine of a tube or barrel to contain ink, having one end closed and the other end fitted with a removable cap, said tube having 90 a slot to receive a liquid absorbent material; said liquid absorbent material; a clamp joined to the tube or barrel by means of a ring clasped around said tube having on either side a projection or tenon fitting 95 into a corresponding indentation or mortise in the clamp; and a spring attached to the tube or barrel with means for regulating the tension of said spring, all substantially as described and illustrated in the accompanying drawing.

Signed at New York city, in the county of New York and State of New York this 11th day of November, A. D. 1920.

LOUIS SARKIS HARPOOTIAN.
